UNITED STATES PATENT OFFICE.

GEORGE J. WUNDER, OF HOWARD, SOUTH DAKOTA.

BAG-HOLDER.

1,157,138.

Specification of Letters Patent.

Patented Oct. 19, 1915.

Application filed January 29, 1914. Serial No. 815,216.

To all whom it may concern:

Be it known that I, GEORGE J. WUNDER, a citizen of the United States, residing at Howard, in the county of Miner, State of South Dakota, have invented certain new and useful Improvements in Bag-Holders; and I do hereby declare the following to be a full, clear, and exact description of the invention, such as will enable others skilled in the art to which it appertains to make and use the same.

This invention relates to improvements in bag holders, and is particularly adapted for use in bagging grain and vegetables, or use in post-offices for holding mail bags.

The principal object of the invention is to provide a simple device which can be readily suspended from a wall or other suitable support, and effectively support the bag, while at the same time holding the mouth of the bag open.

Another object is to provide a simple device of this character which is readily adjustable to different sized bags, and which can be taken apart for packing and occupy very small space.

Other objects and advantages will be apparent from the following description, when taken in connection with the accompanying drawings.

In the drawings: Figure 1 is a perspective view of the device in operation. Fig. 2 is a top plan view. Fig. 3 is an enlarged transverse section on the line 3—3 of Fig. 2. Fig. 4 is an enlarged transverse sectional view on the line 4—4 of Fig. 2.

Referring particularly to the accompanying drawings, 10 represents a suitable eye member formed of a single piece of material, preferably metal and having the ends 11 extending in opposite directions from the lower side of the eye and provided with the interiorly threaded sockets 12. Engaged in these sockets are the threaded ends of the hollow bars 13, and engaged in the outer ends of these bars are the horizontal portions of the angle bars 14. Engaged through the end portions of the hollow bars 13 are set screws 15 for holding the horizontal portions of the bars 14 in adjusted positions slidably within the hollow bars 13. The lower end of the vertical portion of each of the bars 14 is threaded and disposed through an opening in a forwardly extending plate 17. Engaged on the threaded portion of the bar 14, both above and below

the plate 17 are the nuts and washers 18 and 19. Each of the bars 17 is formed with a longitudinally extending elongated slot 20 which registers with a similar slot in a plate 22 disposed under said plate 17. A bolt 23, having a squared shank is disposed through the registered slots and carries on its upper end a winged nut 24. The plates 17 and 22 are thus capable of sliding movement and can be held in such adjusted positions by means of the nut and bolt. The forward or outer end of each of the plates 22 is curved inwardly toward the opposite plate.

Formed in the rear end of each of the plates 17 is an opening 25 in which is engaged a hook 26 carried by one end of a chain 27. The inner end of each of these chains is connected to one end of a coiled spring 28, said spring being disposed beneath, and slightly to the rear of the eye member 10.

A suitable hook 29 is arranged to be attached to a wall or other suitable support, and the eye member 10 engaged thereon.

In the operation of the device, the eye member being engaged on the hook, the bars 14 are adjusted inwardly or outwardly of the hollow bars 13, according to the width of the mouth of the bag. When such adjustment is accomplished, the bars 14 are locked in position by the set screws 15. The plates 22 are then adjusted according to the other dimension of the mouth of the bag. By drawing the outer end of the plates toward each other against the tension of the spring 28, the mouth of the bag can be engaged over said plate, and upon releasing the plates, the spring will draw on the rear ends thereof and cause the outer ends to spread and effectively hold the mouth of the bag open.

By the arrangement of the nuts and washers 18 and 19, the plates 17 can be readily swung without effecting any rotation whatever of the nut 18, thus assuring that the plates will at all times be firmly held on the bars 14. It will also be noted that by removing the lower nuts and washers 18 and 19, and the set screws 15, the device can be quickly disassembled for convenient and compact packing.

While I have shown the members 13 as removably attached to the eye member 10, said members may be made integral therewith.

What is claimed is:

A bag holder comprising an inverted U-shaped member provided with means for the suspension thereof, a pair of arms pivotally mounted on the lower ends of the arms of the U-shaped member, the said pivotal arms extending forwardly and rearwardly of the pivots thereof, and a resilient connec-

tion between the rearward portions of said arms.

10

In testimony whereof, I affix my signature, in the presence of two witnesses.

GEORGE J. WUNDER.

Witnesses:

G. E. HANSON,
J. B. ADKINS.
